UNITED STATES PATENT OFFICE.

LEW HARRY GRIFFITH, OF MOORES HILL, INDIANA.

LAMP ATTACHMENT.

SPECIFICATION forming part of Letters Patent No. 747,063, dated December 15, 1903.

Application filed August 7, 1903. Serial No. 168,667. (No model.)

To all whom it may concern:

Be it known that I, LEW HARRY GRIFFITH, a citizen of the United States, residing at Moores Hill, in the county of Dearborn and State of Indiana, have invented a new and useful Lamp Attachment, of which the following is a specification.

My invention relates to lamp attachments, and especially to a connection between the lamp and its burner, whereby the latter may be tilted backward for filling the lamp, and has for its objects to produce a device of this character of simple construction which in practice will form a strong firm connection between the lamp and its burner, one through which a circulation of air is constantly maintained for obviating accumulation of gas and consequent explosions, and one in which overflowing of the oil while filling the lamp is prevented.

To these ends the invention comprises the novel details of construction and combination of parts more fully hereinafter described.

In the accompanying drawings, Figure 1 is a vertical sectional view illustrating my improved device applied to a lamp. Fig. 2 is a top plan view of the device removed. Fig. 3 is a perspective view of the same. Fig. 4 is a detail sectional view.

Referring to the drawings, 1 indicates my improved connection or coupling comprising a lower section or member 2 and an upper section or member 3, these and the other parts of the device hereinafter described being all composed of any suitable metal, but preferably from sheet-brass.

The lower or primary section 2, which is preferably of circular form, as is also the upper section, is provided with a central opening 4, surrounded by a depending externally-threaded neck or flange 5, designed in practice to screw into the neck 6 of a lamp 7, and with an upstanding peripheral flange 8, entirely surrounding and inclosing the horizontal portion or plate 9 of the member for the purpose which will hereinafter appear.

The upper or secondary section 3 is provided with a central opening 10, adapted in practice to register with the opening 4 and surrounded by an upwardly-extending exter-

nally-threaded neck or flange 11, onto which the burner 12 of the lamp is screwed, and with a depending peripheral flange 13, surrounding the normally horizontal portion or plate 14 of the member.

The members 2 and 3 are pivotally connected at one side, preferably by means of a hinge 15, one leaf of which is attached to the under side of plate 9 and the other to the upper face of plate 14, thus permitting the members 60 to close one upon the other, in which position the flange 8 of member 2, the inner diameter of which is substantially equal to the outer diameter of flange 13, will inclose the latter, which being of a depth substantially equal 65 to the height of flange 8 will consequently bear at its lower edge upon the upper face of plate 9, thus forming between the members an air-space 16, to which air freely enters through openings 17, formed through the 70 plate 14 of member 3.

The sections or members are locked in their closed relation by a catch member 18, pivoted to the plate 14 of member 3 to swing in a horizontal plane and formed adjacent to its outer 75 end to enclasp the horizontal portions of the members, the catch being also provided at its outer end with a finger-piece 19.

In practice the latch will maintain the members in secure locked position for holding the burner in proper position upon the lamp, at which time the lamp-wick will extend downward through the central openings in the members, and a current of cool air will pass through the openings 17 and circulate 85 within the air-space 16 between the members, thus preventing undue heating of the parts and the accumulation of gas, obviating liability of explosions. The latch may be readily manipulated for releasing the members to 90 permit backward tilting of the burner for filling the lamp, during which operation the flange 8 will prevent the escape of any oil which may flow upon the plate 9.

From the foregoing it will be seen that I 95 produce a device of simple construction which will be efficient in operation and one which is admirably adapted for the attainment of the ends in view; but it is to be understood that I do not limit myself to the 100

precise details herein set forth, inasmuch as minor changes may be made therein without departing from the spirit of the invention.

Having thus described my invention, what I claim is—

1. In a device of the class described, the combination with a primary member having a horizontal portion provided with an opening surrounded by a depending neck, of a secondary member pivotally associated with and adapted to close upon the primary member, said secondary member having a horizontal portion provided with an opening surrounded by an upstanding neck, a flange provided upon one of said members for engagement with the other to form an air-space between them when closed, one of said members having an air-inlet opening or openings communicating with the air-space, and means for locking the members relatively in their closed position.
- 15 2. In a device of the class described, the

combination with a primary member having a horizontal portion provided with an upstanding flange and an opening surrounded by a depending neck, of a secondary member pivotally associated with and adapted to close upon and coöperate with the primary member to form an air-space between them when closed, said secondary member having a horizontal portion provided with an opening surrounded by an upstanding neck and one of the members having an air-inlet opening or openings communicating with the air-space, and means for locking the members relatively in their closed positions.

In testimony that I claim the foregoing as my own I have hereto affixed my signature in the presence of two witnesses.

LEW HARRY GRIFFITH.
